SLIDING DOOR ESCUTCHEON PLATE

Sig R. Rechberg, Tujunga, Calif., assignor to Adams Rite Manufacturing Company, Glendale, Calif., a corporation of California

Filed Oct. 13, 1960, Ser. No. 62,483

Term of patent 14 years

(Cl. D50—6)

FIG. 1 is a perspective view of a sliding door escutcheon plate showing my new design;

FIG. 2 is a front elevational view, and

FIG. 3 is a longitudinal sectional view taken substantially on line 3—3 of FIG. 2.

The dominant features of my design reside in the portions shown in full lines.

I claim:

The ornamental design for a sliding door escutcheon plate, as shown and described.
